UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

DESIGN FOR A PANIC-BOLT.

51,768.

Specification for Design. Patented Feb. 12, 1918.

Application filed December 15, 1917. Serial No. 207,374. Term of patent 14 years.

To all whom it may concern:

Be it known that I, HENRY G. VOIGHT, a citizen of the United States, residing in New Britain, county of Hartford, and State of Connecticut, have invented a new, original, and ornamental Design for a Panic-Bolt, of which the following is a specification, when taken in connection with the accompanying drawing.

In the drawing,

Fig. 2 is a side elevation of the same; Fig. 3 is a section on line 3—3 of Fig. 1; Fig. 4 is a top plan view of one of the casings; and

Fig. 5 is a top plan view of the other casing.

What I claim is:

The ornamental design for a panic bolt; substantially as shown.

HENRY G. VOIGHT.
